SAFETYPIN

William C. Lockwood, Chicago, Ill.

Application February 10, 1936, Serial No. 63,102

13 Claims. (Cl. 24—158)

This invention relates to a new and improved clasp pin and the method of making the same.

It is an object of the present invention to provide a pin capable of securing together penetrable materials, such as fabrics, which will be securely and permanently fixed in position and held against accidental opening thereof.

It is another object of this invention to provide a pin of the safety type which will not present an unguarded pointed member even when the catch member is disengaged.

It is a further object of this invention to provide a safety pin which may be used in connection with clothing wherein the pointed member thereof cannot become disengaged so as to puncture the flesh accidentally.

Numerous other objects and advantages will more fully appear during the course and progress of the following specification.

20 Figure 1 is a perspective view of one preferred embodiment of the present invention.

Figure 2 is a perspective view of the embodiment shown in Figure 1 with the slidable clasp member in disengaged position.

25 Figure 3 is a perspective detail view of the head of the pin shown in Figures 1 and 2 with the slid- able catch member removed.

Figure 4 is a plan view of an alternative form of spring portion which may be used in connection with the present invention.

30 Figure 5 is a cross section view of the head of the embodiment shown in Figure 1 about line 5—5 of Figure 1.

Figure 6 is a cross section view of the head portion of the embodiment shown in Figure 2 about line 6—6 of Figure 2.

Figure 7 is a transverse cross section view of the member of the embodiment in Figure 2 about line 7—7 of Figure 2.

40 Figure 8 is a cross section view of an alternative form of brace member which may be used in connection with the present invention.

Figure 9 is a cross section view of another alternative form of brace member which may be used in connection with the present invention.

45 Figure 10 is a cross section view of an alternative form of slidable catch member which may be used in connection with the present invention.

The embodiment of the present invention shown in Figure 1 comprises a spring wire member 1 which is preferably made of suitable spring brass wire of desired gauge and may be circular in cross section. The wire is bent in a continuous spring loop 2, the ends of which are carried forwardly from the U as shown at 3 and 4 re-

spectively in Figure 1. Right angle bends are made in these two extended portions forming a longitudinally extending back member 5 and a front member 6. The front member 6 is considerably shorter than the back member 5 and has a point 7. The back member 5 is extended forwardly and is bent to form a U-bend 8 in the head of the pin and terminates at 9 in such a manner that the termination point 9 thereof is in close juxtaposition to the point portion 7 on the front member 6. A sheet metal clasp member 10 is formed to embrace the head portion 8 of the wire. The clasp 10 is provided with two tubular portions 11 and 12 respectively which slidably embrace the straight portions of the U-shaped bend 8 in the wire of the pin. A small depression 13 is made in this clasp member. The clasp member is also provided with an extending lip 14 which is adapted to overlie the pointed portion 7 of the front member 6 of the pin when the clasp is in engaged position. A second depression 15 may be formed in the underside of the clasp member as is more clearly shown in the cross sectional view, Figure 5. An upturned lip 16 is formed in the inside portion of the clasp member 10 so as to form a closure therefor. A brace member 17 is provided. This brace member is made of a thin sheet of metal and is adapted to be curled about the back member of the pin 5 as shown at 18. The brace is preferably provided with an extended portion 19 which is curled about the termination of the U-bend in the wire at the head of the pin at its termination point 9 as shown at 20 in Figure 3. This brace member extends across the inner plane of the pin between the back member 5 and the front member 6 and has an open faced channel portion 21 formed therein in which channel portion the pointed member 7 of the front member 6 of the pin will lie. The spring loop 2 at the end of the pin is so arranged that the normal springing tendency thereof is to draw the front member 6 and the back member 5 toward each other. Thus, the pointed portion 7 of the front member will normally be springingly held within the channel 21 of the brace 17. The clasp portion is slidable along the head of the pin toward and away from the brace member. The depressions 13 and 15 in the clasp member are so arranged that they do not meet, but leave a free space 22 therebetween. The metal out of which this clasp is made preferably has some springing characteristic so that when the clasp is in engaged position, as shown in Figure 1, that portion of the wire of the pin which forms the U-bend 8 will lie in the enlarged 55

portion 23 of the clasp member. The edges 24 and 25 respectively of the depressions 13 and 15 respectively will tend to hold the clasp in the engaged portion against unauthorized slipping 5 backwardly into disengaged position. When it is desired to disengage the clasp, the clasp may be manually moved backwardly away from the brace member whereupon the U-bend 8 will force the depressions 13 and 15 outwardly, thereby enlarging the space 22 and allowing the catch to slide backwardly over the loop portion 8 until the loop portion 8 slips into the enlarged channel 26 which lies forward of the depressions 13 and 15 respectively as shown in Figure 6. The lip portion 16 is bent upwardly forming a closure and preventing any further retraction of the clasp. When this occurs the depressions 13 and 15 tend to spring back into their original position, narrowing down the intervening space 22 and holding 10 the clasp in disengaged position until such time as it is desired to manually force it back into engaged position again. This retraction of the clasp member brings the lip 14 thereof backwardly along the open faced channel 21, thereby exposing the pointed portion 7 of the front member 6 of the pin. The length of the lip 14 is so adjusted with respect to the amount of slideable movement of the clasp member so that the pointed portion 7 of the pin will be entirely free from 15 engagement therewith so that it may be manually withdrawn from the confines of the open faced channel member 21. It should be noted that the action of the spring loop 2 is such as to maintain the point of the pin in the open faced channel even though the clasp has been moved 20 into disengaged position.

Other modifications of the present invention may be employed. Thus, for instance, the spring loop 28 shown in Figure 4, may be substituted for the spring loop 2 previously described. This spring loop comprises a circular loop 29 and a triangular loop 30, thereby providing a sort of double spring action of greater strength and symmetry. Similarly variations may be made in 40 the brace member 17 such as that shown in Figures 8 and 9. The brace member shown in Figure 8 comprises a continuous piece of sheet metal 31 which is similarly curled about the pin member and is brought downwardly to make a closed structure in the area of the open faced channel portion 21. The brace member shown in Figure 9 is a solid molded structure in which the open faced channel 21 is molded at one end and the pin embracing portion 32 is molded at the other end 45 of an intermediate web portion 33. It is also possible to form a slideable clasp member similar to that shown in Figures 1 and 2 with only one depression. This is illustrated in cross section in Figure 10 and comprises a sheet metal clasp member 34 similar in essential details to the member 10 in Figures 1 and 2. This particular embodiment, however, is provided with only one depression 35 in the head thereof, the other face of the clasp member being a plain surface 36. The intervening space 37 in this embodiment corresponds to the intervening space 32 in the previously described embodiment and the action 50 thereof is substantially similar.

It is thought that the invention and numerous 70 of its attendant advantages will be understood from the foregoing description and it is obvious that numerous changes may be made in the form, construction and arrangement of the several parts without departing from the spirit or scope 75 of the invention, or sacrificing any of its attend-

ant advantages, the form herein described being a preferred embodiment for the purpose of illustrating the invention.

Having thus described the invention, what I claim as new and desire to secure by Letters Pat- 5 ent is as follows:

1. A safety pin having two parallel legs, a coiled spring at one end of the pin integrally formed with said legs, a head portion at the other end of the pin and formed by reversely bending one 10 of said legs to form a reversely extending, parallel portion normally registering with the other leg, an open faced channel disposed in the head with its open face directed outwardly, for receiving one leg of the pin and maintaining the legs 15 substantially parallel, a clasp member on the head and slideable longitudinally along both of said parallel, spaced portions of the head in juxtaposition to the channel portion in the head and adapted to be moved toward and away from said 20 channel member so as to form a closure therefor.

2. A safety pin having two parallel legs, a spring at one end of the pin formed with said legs, a head portion at the other end of the pin, an open faced outwardly disposed channel in the head and in spaced relationship to one of said legs, for receiving the other leg of the pin, said spring being tensioned to urge the leg into the channel, a clasp member movable on the head in juxtaposition to the channel portion in the head and adapted to be moved toward and away from said channel member so as to form a closure therefor, and means integrally formed in said clasp member for holding it selectively in closed 25 and open position with respect to the channel, said other leg of the pin being freely seatable in the channel at all times and being retained solely 30 by said clasp member.

3. A safety pin having two parallel legs, a coiled 40 spring at one end of the pin integrally formed with said legs, a head portion at the other end of the pin, an open faced outwardly disposed channel in the head and in spaced relationship to one of said legs, for receiving the other leg of the pin and maintaining the legs substantially 45 parallel, a clasp member movable on the head in juxtaposition to the channel portion in the head and adapted to be moved toward and away from said channel member so as to form a closure therefor, said coiled spring operating to normally 50 force the leg members toward each other, said other leg of the pin being freely seatable in the channel at all times and being retained solely by said clasp member.

4. A safety pin comprising parallel legs connected together, a spring loop, one of said legs being longer than the other and bent in a reverse U-shape to form a head portion, the other leg being pointed, a clasp member slideable along the U-bend of the longer leg, a brace member rigidly secured to the longer leg intermediate of its length and extending across the head portion of the pin in the plane of the U-shaped bend, being secured at its other end to the free end of the U-shaped bend and having an open faced channel portion adapted to receive the shorter leg of the pin.

5. A safety pin comprising parallel legs connected together, a spring loop, one of said legs being longer than the other and bent in a reverse 70 U-shape to form a head portion, the other leg being pointed, a clasp member slideable along the U-bend of the longer leg, a brace member rigidly secured to the longer leg intermediate of its length and extending across the head portion of 75 the pin.

the pin in the plane of the U-shaped bend, being secured at its other end to the free end of the U-shaped bend and having an open faced channel portion adapted to receive the shorter leg of 5 the pin, said clasp member being adapted to slide over the open faced channel to form a closure therefor.

6. A safety pin comprising parallel legs connected together, a spring loop, one of said legs being longer than the other and bent in a reverse U-shape to form a head portion, the other leg being pointed, a clasp member slideable along the U-bend of the longer leg, a brace member rigidly secured to the longer leg intermediate of its 15 length and extending across the head portion of the pin in the plane of the U-shaped bend, being secured at its other end to the free end of the U-shaped bend and having an open faced channel portion adapted to receive the shorter leg of 20 the pin, said spring loop being adapted to force the parallel legs toward each other.

7. A safety pin comprising parallel legs connected together, a spring loop, one of said legs being longer than the other and bent in a reverse U-shape to form a head portion, the other leg being pointed, a clasp member slideable along the U-bend of the longer leg, a brace member rigidly secured to the longer leg intermediate of its 25 length and extending across the head portion of the pin in the plane of the U-shaped bend, being secured at its other end to the free end of the U-shaped bend and having an open faced channel portion adapted to receive the shorter leg of 30 the pin, said clasp member being adapted to slide over the open faced channel to form a closure therefor, said spring loop being adapted to force the parallel legs toward each other.

8. In a device of the character described, a spring loop comprising a single circular loop having two respective ends extending outwardly 40 therefrom, said respective outwardly extending ends being bent toward each other and extending in such a direction so as to overlie each other for a part of their length, while extending in a relatively straight line, each of said extensions being then bent forwardly in a direction away 45 from the circular loop to form substantially parallel members.

9. A brace member for a safety pin comprising a web having a flat web portion, a retaining portion at one end of the web and an open faced channel formed at the other end of the web, said open faced channel facing outwardly from the 5 web portion.

10. A brace member for a safety pin comprising a relatively thin sheet of metal having a cross section in the shape of a V in which the open branches of the V are closed by an inwardly extending U-shaped loop and in which the pointed end of the V has formed therein a substantially circular retaining recess. 10

11. In a safety pin having substantially parallel legs, a head comprising a web member extending from one leg of the pin a predetermined distance and bearing upon its free end a channel member for the reception of the other leg and for maintaining the legs parallel when so arranged, and a latch member engaging said head 15 and slideable longitudinally to a position enclosing said channel whereby to latch said leg in place. 20

12. In a safety pin having substantially parallel legs, a head comprising a web member extending from one leg of the pin a predetermined distance in the plane of said pin and having formed on its outer free edge a longitudinally extending channel member opening outwardly and having a rear surface against which to accommodate the 30 other leg of the pin for maintaining the legs parallel when so arranged, and a sheath-like member engaging the said head for limited movement longitudinally of the pin to a position engaging about said channel member to maintain the leg 35 in closed position. 25

13. In a safety pin, an apertured head having a portion for receiving the end of the free leg of the pin, a sheath member extending about said head and movable longitudinally of the pin to 40 provide a latch for said leg-receiving portion of the head, said sheath having a thumb depression in a wall adjacent the plane of the safety pin and adapted to engage in said aperture to resiliently maintain the sheath in latched position. 45

WILLIAM C. LOCKWOOD.
